UNITED STATES PATENT OFFICE.

WILLIAM EVENSEN, OF CHICAGO, ILLINOIS, ASSIGNOR TO THE GOSS PRINTING PRESS COMPANY, OF CHICAGO, ILLINOIS, A CORPORATION OF ILLINOIS.

FUDGE-BOX.

1,197,726.

Specification of Letters Patent. Patented Sept. 12, 1916.

Application filed September 11, 1915. Serial No. 50,141.

To all whom it may concern:

Be it known that I, WILLIAM EVENSEN, a citizen of the United States, and residing at Chicago, in the county of Cook and State 5 of Illinois, have invented certain new and useful Improvements in Fudge-Boxes, of which the following is a specification, reference being had to the accompanying drawings.

10 My invention relates to fudge boxes of the type shown in U. S. patent to Borgersen, dated January 5, 1915, No. 1,124,104, and it has for its object the provision of a new and improved form and arrangement of parts.

15 It is one of the objects of my invention to provide improved means for securing the fudge box upon its shaft.

It is another specific object of my invention to provide improved means for locking 20 up and unlocking the box as may be desired for changing the contents as additional news is brought in during the run of the press.

It is another object of my invention to improve devices of this type in sundry 25 details hereinafter pointed out.

The preferred means by which I have accomplished my several objects are illustrated in the accompanying drawings and are hereinafter specifically described.

30 That which I believe to be new and desire to cover by this application is set forth in the claims.

In the drawings,—Figure 1 is a view of the fudge box in position upon its shaft, 35 one end of the shaft being broken away; Fig. 2 is a view of the parts shown in Fig. 1 with the fudge box removed therefrom; Fig. 3 is a central longitudinal section through the fudge box and the parts supporting the same, being substantially a section taken on line 3—3 of Fig. 1; Fig. 4 is an outer face view of my improved fudge box with the lock-up slide-block removed therefrom; Fig. 5 is a side view of the parts 40 shown in Fig. 4; Fig. 6 is a view of the parts shown in Fig. 4 as seen from the right therein; Fig. 7 is an end view of the said parts as seen from the left in Fig. 4; Fig. 8 is an enlarged detail showing one end of my improved fudge box; Fig. 9 is an end 45 view of the parts shown in Fig. 8 as seen from the right in said Fig. 8, a lock-up tool being shown in operative position therein; Fig. 10 is a transverse vertical section 50 through my improved fudge box, being sub-

stantially a section taken on line 10—10 of Fig. 8; Fig. 11 is a face view of the plate shown in Fig. 3 for supporting the left-hand end of the spacers as shown in Fig. 3; Fig. 12 is a detailed view of the eccentric 60 employed for moving the lock-up slide-block; and Fig. 13 is a perspective view of the operative portion of the lock-up tool.

Referring to the several figures of the drawings, in which corresponding parts are 65 indicated by the same reference characters,— 20 indicates the fudge box shaft having fixed thereon in any suitable manner a sleeve 21 comprising rings 22—23, in the construction shown formed integrally with the hub, 70 the left-hand faces of such rings as shown in Fig. 3 being beveled out. As shown in Fig. 1, the left-hand end of the sleeve 21 is provided with a gear 24 by which the shaft is adapted to be driven from any suitable 75 source of power. As is best shown in Fig. 2, the sleeve or hub 21 is provided with a plurality of keys 25 spaced circumferentially thereof, such keys being adapted to space in proper position a plurality of fudge 80 boxes provided with suitable keyways adapted to fit snugly over such keys.

In Figs. 3 and 10 the keyway of the fudge box there shown is indicated by the numeral 26.

The fudge box comprises a heavy plate 27 upon which type or other suitable printing elements are adapted to be mounted, as hereinafter described. The plate 27 is adapted to be secured upon the hub or 90 sleeve 21 by means of an arc-shaped beveled portion 28 formed integrally therewith at one end and two beveled lugs 29—30 formed integrally therewith at its other end. The plate 27 is placed 95 upon the hub 21 with the beveled portion 28 extending under the beveled edge of the ring 22, the slot 26 of the plate 27 being inserted over the key 25. The left-hand end of the plate 27, as shown in Figs. 1 and 3, 100 is then clamped in position by means of a clamping plate 31, which is secured by means of a cap-screw 32 upon the hub 21. As is best shown in Fig. 1, the screw 32 passes through a slot 33 extending circumferentially of the slightly curved plate 31, whereby the plate 31 can be slid to one 105 side so as to permit the lug 29 to pass downward through a notch 34 of the said plate 31 so as to render it unnecessary to remove the 110

plate 31 entirely from the hub 21. After the plate 27 has been placed in operative position, the clamping plate 31 is then slid circumferentially of the hub so as to bring 5 its edge over the beveled lugs 29-30, whereupon the plate 31 is tightened in position through the medium of the cap-screw 32. As is best shown in Fig. 3, the plate 31 is provided at one edge with a rib 35, 10 whereby the tightening of the screw 32 serves to force the opposite edge of the plate 31 very firmly downward into engagement with the lugs 29-30, serving thus to clamp the plate 27 very securely upon the hub 21.

15 The means for holding the type or other printing devices upon the plate 27 comprises a plurality of spacers 36 which are held in position upon the said plate 27 by means of a slotted spacing ring 37 at one end and a 20 slotted spacing ring 38 at the opposite end. The said spacers are additionally held in position by means of slots 39 extending longitudinally of the plate 27 between the rings 37 and 38, as best shown in Fig. 4. The 25 ring 38 is formed, in the construction shown, integrally with the plate 27, while the ring 37 is formed separately therefrom and inserted fixedly in position in a suitable recess in a head 40 formed integrally with the 30 plate 27. Heavy plates 41-42 are secured at the opposite edges of the plate 27 by means of screws, or in any other suitable manner. By reason of the head 40 extending over the spacing ring 37 as shown in 35 Fig. 3, the spacers 36 are held against withdrawal from the ring 37 by radial movement at that end of the plate 27. At the opposite end the spacers 36 are held against removal by a radial movement by means of 40 a movable head 43 mounted as hereinafter described upon the plate 27. As is shown in Fig. 3, when the head 43 is moved to the limit of its movement to the left in such figure, it extends over the spacing ring 38, 45 thus effectually preventing the withdrawal of the spacers 36.

The printing devices which I prefer to use are in the form of slugs such as are produced by an ordinary linotype machine, but 50 I do not wish to be restricted to the use of this form of printing devices except as hereinafter specifically claimed. In some of the figures slugs 44 are shown in position between the several spacers 36. The ends of 55 the slugs 44 are held in position by means of knife-like ribs 45-46 on the heads 40-43, respectively, said ribs being adapted to cut into the ends of the slugs as shown in Fig. 3 when the head 43 is forced to the left 60 in said figure into locking position.

The means for moving the head 43 into locking position comprises a slide-block 47, which is mounted upon the plate 27 so as to be slidable longitudinally thereof. As is 65 best shown in Fig. 8, the head 43 is con-

nected to the slide-block 47 by means of two lag-screws 48 which pass through suitable openings in the slide-block 47 and have screw-threaded engagement with the head 43. The slide-block 47 is provided with a plurality of sockets 49 opening at their 70 ends upon the head 43, each of said sockets being provided with a coiled spring 50. As will be readily understood, the springs 50 tend to hold the head 43 away from the slide-block 47 to the limit of their movement as controlled by the lag-screws 48.

For the movement of the slide-block 47 longitudinally of the plate 27, I have provided an eccentric block 51 revolvably mounted in the slide-block 47. The eccentric block 51 is held in position in the slide-block 47 by means of a screw 52 operating in a circumferential groove 53 in the periphery of the eccentric block. A pin 54 mounted eccentrically relative to the block 51, and preferably formed integrally therewith, is revolvably mounted in a block 55 slidably mounted in a slot 56 formed in the upper face of the plate 27. By a rotation of the eccentric block 51, the slide-block 47 is moved longitudinally of the plate 27 by reason of the eccentric positioning of the pin 54.

The eccentric block 51 is provided with a square socket 57 in its upper end, in which a tool 58 is adapted to be inserted for turning the said eccentric block. The block 51 is provided with two pins 59-60 slidably mounted in horizontal position therein, said pins being of such length as to extend from the exterior surface of the block to the face of the socket 57. The said pins, however, are free to move slightly inward to the positions shown in Fig. 12 so that their inner ends extend beyond the faces of said socket 57. A third pin 61 is mounted in the eccentric block at right angles to the pins 59-60. This pin 61 is also slidably mounted in horizontal position, but is of such a length as to extend beyond the periphery of the block 51 or beyond the face of the socket 57. Mounted in the slide-block 47 on the same level with the pins 59-60 there is a pin 62 provided with a coiled spring 63 tending to hold it to the limit of its movement to the right in Fig. 8.

With the slide-block 47 in its unlocked position moved to the right to the limit of its movement in that direction in Figs. 3 and 8, the slugs 44 can be lifted easily and quickly out of the box and readily replaced by other slugs or printing devices. With the parts in that position, the pin 61 will have its outer end in position opposite one of two shallow recesses 64 formed in the wall of the opening in which the eccentric block 51 is mounted. The pin 60 will be in the position occupied by the pin 59 in Fig. 8, the head of the pin 62 being in engagement with the opening in which such pin 60 is 130

mounted, the pin 62 thus serving to lock the eccentric block 51 against rotation. Upon the insertion of the tool 58 into the socket 57 for the turning of the eccentric block 51, the 5 pin 60 will be forced outward, forcing the pin 62 out of engagement with the eccentric block 51, thus permitting the rotation of the eccentric block 51, the pin 61 in the meantime being forced inward with its inner 10 end engaging a recess 65 in the tool. The eccentric block 51 can then be turned in either direction for moving the slide-block 47 to the left in Fig. 8. By reason of the engagement of the pin 61 with the recess 65 15 of the tool, the tool 58 cannot be withdrawn until the eccentric block 51 has been given a rotation of one hundred and eighty degrees, bringing the pin 61 into line with the other one of the two notches or recesses 64. 20 At the same time that the pin 61 is brought into line with the notch 64 the pin 59 is brought into line with the pin 62, which is forced to the right into locking position, as shown in Fig. 8. By reason of this construction 25 and arrangement it is necessary that the eccentric block 51 be given a complete rotation of one hundred and eighty degrees to either its locked position as shown in Fig. 8 or to its unlocked position before the operating tool 58 can be inserted or withdrawn from the socket 57.

By reason of my construction heavy springs 50 may be employed for providing the requisite yielding pressure upon the 30 movable head 43. At the same time the springs 50 are out of action as opposing the operative movement of the head 43, except at the very end of the operative movement, the major portion of the movement of the 35 head 43 being accomplished thus without the opposition of the springs 50. By reason of the arrangement of the pins 59, 60, 61, and 62 in connection with the tool 58, protection is afforded against incomplete locking 40 of the slide-block 47, such as might permit a retraction of the head 43 out of engagement with the slug 44 and the spacers 36.

That which I claim as my invention, and desire to secure by Letters Patent, is— 50 1. The combination of a shaft, a fudge box, and means for securing said fudge box on said shaft, comprising a lug projecting from one end of said fudge box, a clamping plate movable circumferentially of the shaft 55 into position over said lug, and means for forcing said clamping plate toward said shaft overlying said lug.

2. The combination of a rotary member, a fudge box in position on said rotary member, a clamping plate movable into and out of position with one edge portion overlying one end of said fudge box, means for forcing 60 said clamping plate toward said rotary member for locking the end of said fudge box securely in position on said rotary member,

and other means for holding said clamping plate, when in operative clamping position, against turning out of engagement with said fudge box and against movement longitudinally of the rotary member away from the 70 fudge box.

3. The combination of a rotary member provided with a circumferentially-extending shoulder, a fudge box in position on said rotary member a short distance from said 75 shoulder, a clamping plate movable into and out of position with its inner edge portion overlying the edge of said fudge box adjacent to said shoulder, and means for forcing said clamping plate toward said rotary 80 member, the outer edge portion of said clamping plate when in operative clamping position being in contact with said shoulder whereby the clamping plate is held against turning out of engagement with said fudge- 85 box and against movement longitudinally of said rotary member away from the fudge box.

4. The combination of a shaft, a fudge-box, and means for securing said fudge-box 90 on said shaft, comprising a clamping-plate movable into and out of position overlying one end of said fudge-box, means for forcing said clamping-plate toward said shaft and for holding the plate in clamping position, and means independent of said plate-holding means serving to prevent the clamping plate when in clamping position from moving longitudinally of the shaft away from the fudge-box, one of the inter-engaging 100 faces of said fudge-box and said clamping-plate being beveled whereby the pressure of the clamping-plate toward the shaft tends to force the fudge-box longitudinally of the shaft in the direction away from the clamping-plate. 105

5. The combination of a rotary member having an undercut shoulder at one end, a fudge-box extending at one end under said shoulder, and means coöoperating with said shoulder for securing said fudge-box on said rotary member, comprising a second shoulder upon said rotary member beyond the opposite end of said fudge-box, a clamping-plate movable into and out of position overlying the last-mentioned end of said fudge-box, the outer edge of said plate being adapted to engage said second shoulder, and means for forcing said clamping plate toward said rotary member, one of the inter-engaging 110 faces of said fudge-box and said clamping-plate being beveled whereby the pressure of the clamping-plate toward the rotary member tends to force the fudge-box longitudinally of the rotary member into firm engagement with said first-mentioned shoulder. 115 120 125

6. The combination of a shaft, a plurality of fudge boxes, and means for securing said fudge boxes on said shaft, com- 130

prising a plurality of keys fixed on said shaft at intervals circumferentially thereof, a ring fixed on said shaft and beveled out at one edge adapted to receive beveled 5 end bearing portions of said fudge boxes, a plurality of clamping plates one for each of said fudge boxes adapted to engage beveled bearing portions at the opposite ends of said fudge boxes, and means for drawing 10 said clamping plates firmly down upon said bearing portions for tightening said fudge boxes securely in position upon the shaft, each of the fudge boxes being provided with a longitudinally-extending groove adapted 15 to coöperate with one of said keys for holding the fudge box against movement circumferentially of the shaft.

7. In a fudge box, the combination of a 20 plate, a head rising from said plate at one end thereof, a slotted spacing ring located in a suitable recess in one face of said head, a second slotted spacing ring extending upward from said plate near its opposite end, a second head movably mounted on said 25 plate adapted to be moved into and out of position overlying said second slotted spacing ring, and means for moving said second head relative to said plate.

8. In a fudge box, the combination of a 30 plate, means mounted on said plate for holding in position a plurality of printing devices, comprising a head movable longitudinally of the plate, and means for moving said head relative to said plate comprising 35 a plurality of springs adapted to bear upon said head, and means for moving said springs for moving said head yieldingly into locking position.

9. In a fudge box, the combination of a 40 plate, means mounted on said plate for holding in position a plurality of printing devices, comprising a head movable longitudi-

nally of the plate, and means for moving said head relative to said plate, comprising 45 a slide-block, means for moving said slide-block longitudinally of the plate, and yielding means interposed between said slide-block and said head.

10. In a fudge box, the combination of a 50 plate, means mounted on said plate for holding in position a plurality of printing devices, comprising a head movable longitudinally of the plate, and means for moving 55 said head relative to said plate, comprising a slide-block, means for moving said slide-block longitudinally of the plate, and springs carried by said slide-block adapted to bear upon said head for moving it yieldingly into locking position.

11. In a fudge box, the combination of a 60 plate, means mounted on said plate for holding in position a plurality of printing devices, comprising a head movable longitudinally of the plate, and means for moving 65 said head relative to said plate, comprising a slide-block, means for moving said slide-block longitudinally of the plate, springs carried by said slide-block adapted to bear upon said head for moving it yieldingly into locking position, and means connecting said 70 head with said slide-block for limiting the movement of said parts away from each other under the action of said springs.

12. In a fudge box, the combination of 75 a plate, means mounted on said plate for holding in position a plurality of printing devices, comprising a head movable longitudinally of the plate, and means for moving 80 said head relative to said plate, comprising a slide-block, yielding means interposed between said slide-block and said head, and means comprising an eccentric for moving said slide-block longitudinally of the plate.

WILLIAM EVENSEN.
